SINK MAT OR SIMILAR ARTICLE

Charles O. Bliss, Los Angeles, Calif.

Application April 14, 1958, Serial No. 50,472

Term of patent 14 years

(Cl. D9—6)

FIG. 1

FIG. 2

Fig. 1 is a top plan view of a sink mat or similar article showing my new design;

Fig. 2 is an enlarged sectional view on the line 2—2 of Fig. 1.

The entire surface of the mat has the same appearance as the quarter indicated by the dot and dash line A—B—C. Both sides of the mat have substantially the same appearance.

I claim:

The ornamental design for a sink mat or similar article, substantially as shown and described.
